UNITED STATES PATENT OFFICE.

JOHN DEININGER, OF ULM, GERMANY.

ICE-CRUSHER.

1,103,132.

Specification of Letters Patent.

Patented July 14, 1914.

Application filed December 16, 1912. Serial No. 737,016.

To all whom it may concern:

Be it known that I, JOHN DEININGER, a subject of the German Emperor, residing at Ulm-on-the-Danube, in Germany, have 5 invented certain new and useful Improvements in Ice-Crushers, of which the following is a specification.

This improvement relates to ice crushers as hand tools by means of which ice can be 10 easily and quickly broken to small pieces, and which comprise a number of pointed pins secured to a plate and passing through a spring controlled plate which is adjustable in the direction of the pins, is guided 15 by the same, and is pressed downward by springs. The said plate coöperates in crushing and prevents the series of pins from being choked, and the ice from splashing.

20 In the accompanying drawing in which the same reference letters indicate the same parts throughout, Figures 1, 3 and 5 are vertical sections of such ice crushers which differ from each other by the construction 25 of the said spring plate. Figs. 2, 4 and 6 are bottom views of the ice crushers in Figs. 1, 3 and 5, Fig. 7 is a cross-section on line A—B of Figs. 1, 3 and 5, Fig. 8 is a partial vertical section, showing another construction 30 of means for limiting the outward movement of the spring plate in Figs. 1-6, Fig. 9 is a cross-section on line C—D of Fig. 8, Fig. 10 is a partial vertical section of an ice crusher shown in Figs. 1-6, showing another means for limiting the outward 35 movement of the above spring plate.

According to Figs. 1-7, to the lower face 40 of a plate *b* and at a right angle to the same, are secured the pins *a* preferably made of steel and pointed at their free end, distributed as uniformly as possible. On the upper face of the plate *b* it is provided with a hub *r* in the center, and preferably with strengthening ribs *s*. In the hub *r* is 45 cured at a right angle to the plate *b*, a tubular sleeve *c*. Into the lower open end of the said sleeve *c* projects loosely a head *n* mounted at the free end of a rod *e* which is 50 secured at its other end to a spring plate *d'* (Figs. 1 and 2) or *d''* (Figs. 3 and 4) or *d'''* (Figs. 5 and 6), of approximately the same size as the plate *b* and used for the above mentioned purpose. This spring plate is shown of different construction in 55 the figures, as will be hereinafter described.

It is provided with holes *k* through which the pins *a* pass loosely. It is guided, on the one hand, by means of the pins *a*, and on the other hand, by means of the above mentioned head *n* of the rod *e* in the sleeve *c*. In the sleeve *c* is mounted a helical spring *f* pressing at the bottom against the head *n*, and at the top against a cotter pin *h* connecting the free end of the sleeve to a handle *g* arranged concentrically with the same. The spring plate is therefore controlled by the action of the spring *f* which has the tendency to keep it in the end position shown in the drawing and determined by the engagement of the heads *p* with the plate *b*. These heads *p* are mounted at the free end of bolts *o* secured to the upper face of the spring plate parallel to the pins *a* and passing through the plate *b* and used for further guidance of the spring plate. 75 If the spring plate is pressed toward the plate *b* to which it can be brought quite close, the former plate will be pushed back again into the end position illustrated, by the action of the spring *f* after the pressure 80 ceases.

In Figs. 8 and 9, the above mentioned bolts *o* are connected together, above the plate *b*, by a plate *t* which is provided in the center with a hole for the passage of the hub *r*. The bolts are in this case preferably in the planes of the ribs *s* which are then provided with bosses *u* for the passage of the bolts. The plate *t* vertically reciprocates with the spring plate, and by engagement with the ribs *s* limits the outward 85 movement of the spring plate. 90

Another method of limiting this outward movement of the spring plate is shown in Fig. 10. The tubular sleeve *c* is reduced at 95 the point *v*, and with the said reduced portion engages the above mentioned head *n*. In that way, the plate *b* is not affected at all by the recoil of the spring plate. The ribs *s* are omitted, but of course may also 100 be used.

The above mentioned spring plate *d'* is provided, according to Figs. 1 and 2, at the lower face with short pointed pins *i* which participate in the crushing and render the 105 ice smaller and finer.

In the construction shown in Figs. 3 and 4, the spring blade *d''* is provided with a downward flange *l* with sharp teeth *m* participating in the crushing of the ice.

In the construction shown in Figs. 5 and 6, the spring blade d^3 is covered with short pointed pins and has moreover a downward flange l with sharp teeth m .

5 The crushing of ice by means of the crusher described, is effected by seizing the handle g and making a ramming movement with the crusher against the pieces of ice to be crushed. The pins a first split the 10 pieces of ice, the spring plate d' or d^2 or d^3 being simultaneously raised. On the ice crusher being raised for further blows, by which the split pieces of ice are reduced by the pins a and the pins i or the teeth m , 15 so that the action is a double one, the spring plate is projected each time by a spring f against the free ends of the pins a . In that way, it removes any bits of ice accumulating between the pins. The ice is very quickly 20 and easily reduced to pulp as required chiefly in confectioners' shops.

What I claim as my invention and desire to secure by Letters Patent is:—

1. In an ice crusher comprising a main 25 plate, a spring plate, pointed pins secured to the main plate and passing through holes in the spring plate and guiding said spring plate, a spring adapted to separate the plates, means for counter-guiding the spring 30 plate and means for limiting its outward movement, the combination of short point-

ed pins on the lower surface of the spring plate.

2. In an ice crusher, comprising a main plate, a spring plate, pointed pins secured 35 to the main plate and passing through holes in the spring plate and guiding said spring plate, a spring adapted to separate the plates, means for counter-guiding the spring plate and means for limiting its outward 40 movement, the combination of a downwardly extending serrated flange upon the spring plate.

3. In an ice crusher, comprising a main plate, a spring plate, pointed pins secured 45 to the main plate and passing through holes in the spring plate and guiding said spring plate, a spring adapted to separate the plates, means for counter-guiding the spring plate and means for limiting its outward 50 movement the combination of short pointed pins on the lower surface of the spring plate and a downwardly extending serrated flange thereon.

In testimony whereof I have signed my 55 name to this specification in the presence of two subscribing witnesses.

JOHN DEININGER.
